UNITED STATES PATENT OFFICE

128,382

DESIGN FOR A TEXTILE PILE FABRIC

John J. Repp, Philadelphia, Pa., assignor to Collins & Aikman Corporation, Philadelphia, Pa., a corporation of Delaware

Application April 22, 1941, Serial No. 100,553

Term of patent 14 years

To all whom it may concern:

Be it known that I, John J. Repp, a citizen of the United States, residing at 5228 Schuyler Street, Philadelphia, Philadelphia County, State of Pennsylvania, have invented a new, original, and ornamental Design for a Textile Pile Fabric, of which the following is a specification, reference being had to the accompanying drawing, forming part thereof. The figure is a plan view of a piece of textile pile fabric showing my new design.

The characteristic feature of my design resides in the parallel straight ribs, the surface of each of which is arcuated convexly, the crown portion being soft and the low portions being firm, the low portions of next adjacent ribs merging together, the fabric presenting an overall undulating appearance.

I claim:

The ornamental design for a textile pile fabric, as shown and described.

JOHN J. REPP.
